UNITED STATES PATENT OFFICE.

JOHN J. TOKHEIM, OF CEDAR RAPIDS, IOWA.

VACUUM GASOLENE-RENOVATOR.

1,248,950.

Specification of Letters Patent. Patented Dec. 4, 1917.

Application filed March 30, 1916. Serial No. 87,781.

To all whom it may concern:

Be it known that I, JOHN J. TOKHEIM, a citizen of the United States, residing at Cedar Rapids, in the county of Linn and State of Iowa, have invented a new and useful Vacuum Gasolene-Renovator, of which the following is a specification.

It is the object of the present invention to provide novel means for effecting a renovation of gasoline or any like volatile cleaning liquid, to provide novel means whereby the liquid is vaporized and condensed, and to provide novel means for caring for the impurities which are removed from the gasoline.

Another object of the invention is to provide novel means for supplying gasoline to the apparatus, and to provide novel means for caring for the water of condensation produced by the steam whereby gasoline or other liquid is vaporized.

With the above and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings:—

Figure 1 shows the invention in side elevation, parts being broken away;

Fig. 2 is an elevation showing one end of the structure;

Fig. 3 is an elevation showing the other end of the structure;

Fig. 4 is a fragmental section taken on the line 4—4 of Fig. 1; and

Fig. 5 is a section taken on the line 5—5 of Fig. 1.

In the drawings, there is shown a supply tank 1, equipped with an inlet 2 and having a vent 3. At one end, the supply tank 1 is provided with a clean-out plug 4, the other end of the supply tank 1 carrying a gage glass 5. Below the supply tank 1 is a distillation tank 6. A pipe 7 forms a communication between the supply tank 1 and the distillation tank 6, and enters the distillation tank, the pipe 7 carrying at its upper end, a valve seat 8 located within the supply tank 1. Coöoperating with the valve seat 8 is an upwardly opening valve 9 pivotally connected with a rod 10 passing through an opening

11 in the top of the supply tank 1. The upper exposed end of the rod 10 is pivoted eccentrically to a cam 12 adapted to coöperate with the top of the supply tank 1. Mounted to reciprocate on the pipe 7 and located within the distillation tank 6 is a float 14. Pivoted to the float 14 are depending links 15 which, in their turn, are pivoted to the outer ends of levers 16 fulcrumed intermediate their ends on a frame 17 depending on the lower end of the pipe 7. The frame 17 includes a seat 17^a adapted to coöperate with a downwardly closing valve 18 pivoted to the inner ends of the levers 16. At one end, the distillation tank 6 is supplied with a clean out door 19, the other end of the distillation tank carrying a gage-glass 20. In the distillation tank 6 and located near to the top thereof, is a trough or collector 21. A pipe 22 is located exteriorly of the tank 6, and into the pipe 22 the trough 21 discharges. A nozzle 23 enters the pipe 22 at its upper end. A cold water pipe 24 communicates with the nozzle 23 and carries a valve 25. A steam pipe 26 enters the tank 6, and, if desired, comprises a plurality of branches, each of the branches being equipped with perforations 27. Exteriorly of the distillation tank 6, the steam pipe 26 is equipped with a valve 28.

Disposed below the distillation tank 6 is a condenser tank 29 in which is disposed a sinuous conduit comprising a plurality of inclined pipes 30 and headers 31 at the ends of the condenser tank 29. The upper end of the conduit defined by the pipes 30 and the headers 31 communicates with the lower end of the pipe 22. At one end of the condenser tank 29 and adjacent the top thereof is located a water discharge pipe 32. Disposed at the opposite end of the condenser tank 29 and entering the bottom thereof is a water supply pipe 33. Disposed below the condenser tank 29 is an upright separator 34. The upper end of an exterior pipe 35 communicates with the lower end of the sinuous conduit formed in the condenser tank 29 by the pipes 30, the lower end of the pipe 35 entering the separator 34. Disposed within the separator 34 is an upright outer sleeve 36, the upper end of which is secured to the top of the separator. The side of the sleeve 36 which is remote from the pipe 35 is provided near to the top of the separator with an opening 37. Disposed within the outer sleeve 36 is an inner sleeve

- 38 secured to the top of the separator. The inner sleeve 38 has a small air vent 38^a near its top which prevents a siphoning action through the pipe 39 hereinafter mentioned.
- 5 The lower ends of the sleeves 38 and 36 are spaced apart from the bottom of the separator 34. A water outlet 39 enters the bottom of the separator 34 within the inner sleeve 38. A gasoline outlet pipe 40 projects upwardly through the bottom of the separator 34 and extends between the outer sleeve 36 and the inner sleeve 38, the upper end of the pipe 40 being located at a greater elevation than the upper end of the pipe 39.
- 10 In the bottom of the separator 34 may be located a clean out plug 41.
- 15 Disposed beneath the condenser tank 29 and at the side of the separator 34 is an upright receiver which may be of circular contour. The receiver 42 is supplied with a gage glass 43, and with a drain 44 including a valve 45. At one side and intermediate its ends, the receiver 42 is provided with a sampling cock 46. Access may be had to the 20 receiver 42 by means of a plug 47. A pipe 48 enters the distillation tank 6, adjacent the bottom of the distillation tank, and leads to the receiver 42, the pipe opening into the receiver at a point near the top 25 thereof.

The structure above described may be mounted upon a suitable frame 49, indicated in Fig. 1 of the drawings, but broken away, in order that the essential features of the 30 invention may not be obscured, the specific structure of the frame being immaterial, should it be necessary to use a frame at all.

The practical operation of the device is as follows:

- 40 Gasoline is permitted to flow into the tank 1 through the inlet 2, the cam lever 12 being manipulated to raise the rod 10 and the valve 9, whereupon the gasoline will flow into the distillation tank 6 and by the pipe 48 into the receiver 42, until the receiver 42 is nearly filled with impure gasoline. Subsequently the impure gasoline rises in the distillation tank 6 until the float 14 rises and closes the valve 18. The hand valve 9 is 45 used only when the valve 18 fails to operate automatically.

- 50 Steam is introduced into the distillation tank 6 by way of the pipe 26, the steam passing outwardly into the distillation tank, 55 through the perforations 27, in the pipe. The steam thus introduced into the distillation tank 6, converts the gasoline therein into a moist vapor. The most of the dirt and other impurities remain in the tank 6. 60 The gasoline vapor in the tank 6 passes by way of the collecting trough 21 into the pipe 22. By means of the nozzle 23 water is introduced into the upper end of the pipe 22. This water, which is cold, exercises two functions. First, it serves to wash the vapor, and, 65

it creates a diminution of pressure in the pipe 22, so that there is a tendency for the gasoline vapor to be sucked into the pipe 22, from the tank 6, by way of the trough 21.

From the pipe 22, the gasoline vapor passes into the sinuous conduit formed in the tank 29 by the pipes 30. The gasoline vapor is condensed by the water which has been admitted into the tank 29 through the water supply pipe 33. This condensation of the vapor further reduces the pressure in the pipe 22 and tends to create a suction through the pipe 22. From the lower end of the conduit formed by the pipes 30, gasoline flows through the pipe 35 into the separator 34. Dirt and impurities which remain in the gasoline, tend to gravitate at the bottom of the separator 34. The separator 34 contains water which stands as high as the top of the pipe 39. In the separator 34, the gasoline is compelled to traverse a round-about path on top of the water, the gasoline moving in opposite directions in two streams around the outside of the outer sleeve 36, and passing into the space between the sleeves 36 and 38 through the opening 37. The gasoline ultimately leaves by means of the pipe 40, in a clean condition. As the level of impure gasoline within the distillation tank 6 is lowered, the float 14 moves downwardly, opening the valve 18 and permitting impure gasoline to flow from the supply tank 1 into the distillation tank 6. The operation of the device, therefore, is practically continuous.

The water of condensation from the steam emitted by the steam pipe 26 is received by the tank 6, the water of condensation flowing by way of the pipe 48 into the receiver 42 which is filled with impure gasoline. The impure gasoline in the receiver 42 is replaced by water, the impure gasoline rising through the pipe 48 into the tank 6. The cock 46 may be opened, to permit a sampling of the contents of the receiver 42.

The distillation tank 6, the condenser 29 and the separator 34 are of primary importance. It is desirable to use also the supply tank 1 and the receiver 42 to secure the most perfect results, but, if desired, either the supply tank 1 or receiver 42, or both of them, may be omitted at the will of the user.

Having thus described the invention what is claimed is:—

1. In a device for purifying gasoline and similar cleaning liquids, a distillation tank; a supply tank communicating with the distillation tank; a float-operated valve controlling the passage of liquid from the supply tank to the distillation tank and responsive to changes of level in the distillation tank; a steam pipe entering the distillation tank; a receiver located below the distillation tank; a conduit leading from the distilla- 125

tion tank to the receiver; a separator; a conduit leading from the distillation tank to the separator; a condenser through which the last specified conduit passes; and a 5 source of cold water supply opening into the last specified conduit between the distillation tank and the condenser.

2. In a device for purifying gasolene and similar cleaning liquids, a distillation tank; 10 a separator; a closed conduit leading from the distillation tank to the separator; means for heating the distillation tank; a condenser through which the conduit passes; and means for introducing a reduced jet of 15 cold water into the closed conduit between the distillation tank and the separator.

3. In a device of the class described, a

still; a receiver disposed below the still; a conduit connecting the receiver and the still; means for supplying impure liquid to the 20 still; and means for supplying steam to the still, the receiver constituting means for separating the water of condensation from the impure liquid, and the conduit constituting means for returning the impure 25 liquid to the still.

In testimony that I claim the foregoing as my own, I have hereto affixed my signature in the presence of two witnesses.

JOHN J. TOKHEIM.
